COMBINED CHAIR AND TRAY

John E. Beardmore, Chicago, Ill., assignor to Karoll's, Inc., Chicago, Ill., a corporation of Illinois

Filed July 17, 1959, Ser. No. 56,821

Term of patent 14 years

(Cl. D33—11)

Figure 1 is a perspective view of a combined chair and tray showing my design; and

Figure 2 is a top plan view of the same.

The side of the chair not shown is like the side shown while the back of the chair is conventionally plain.

The design is characterized by the rectangular tray member in combination with the elongated, uniformly proportioned horizontal support frame which is disposed in contiguous relationship to the side members whereby to form flush thickened chair arms, all as shown.

I claim:

The ornamental design for a combined chair and tray, substantially as shown and described.
